ALEXANDRE GASTEL.

Improvement in Iron Planing Machines.

No. 124,676.

Patented March 19, 1872.

FIG. 2

UNITED STATES PATENT OFFICE.

ALEXANDRE GASTEL, OF PHILADELPHIA, PENNSYLVANIA, ASSIGNOR TO HIMSELF AND CHARLES E. MUTRUX, OF SAME PLACE.

IMPROVEMENT IN IRON-PLANING MACHINES.

Specification forming part of Letters Patent No. 124,676, dated March 19, 1872.

To all whom it may concern:

Be it known that I, ALEXANDRE GASTEL, of the city and county of Philadelphia and State of Pennsylvania, have invented an Improvement in Machines for Planing Metal; and I do hereby declare that the following is a full, clear, and exact description thereof, reference being had to the accompanying drawing making part of this specification, in which—

Figure 1, Plate 1, is a section taken longitudinally and vertically through the planer on one side of its center. Fig. 2, Plate 2, is a section taken vertically and transversely through the machine in the plane indicated by dotted line *x x*, Fig. 1.

Similar letters of reference indicate corresponding parts in the two figures.

The object of this improvement is to hold the traveling bed-plate of a planer down firmly on its ways and prevent trembling by means of a yoked brace, which is applied to a fixed bar of an anti-friction wheel that works on top of a flanged rack on the bottom of the said bed-plate, and which is also applied to the shaft of the wheel which engages with said rack, thereby forming, in connection with one side of the frame of the machine, a quadrangular brace, as will be hereinafter described.

The following description of my invention will enable others skilled in the art to understand it.

In the accompanying drawing, A A represent the horizontal and parallel ways of the bed-frame, which are grooved and receive tongs formed on the bottom of the bed-plate or table B, as shown in Fig. 2. To the sides of the bed-frame is bolted the upright frame for carrying the slides. D is the vertical slide; E' the horizontal slide, moved by a screw, S. E is a carrier, which has a slight circular motion, and b is a pivoted cutter-block, carrying a cutting-tool, a. The parts above described may be constructed in the usual well-known manner. On the bottom of the traveling-bed B a rack-plate, c, is formed, which extends the entire length of this bed, and which is flanged at e and toothed so as to form a rack for receiving the teeth of a spur-wheel, N, on a hor-

izontal transverse shaft, H. This wheel N receives motion from a driving-shaft, o, acting through the medium of a pinion, n, a large spur-wheel, N', and a pinion, n', on a shaft, o', shown in Fig. 1. On top of the rack e is applied an anti-friction holding-down wheel, f, the axis of which is in a vertical plane intersecting the axis of the shaft H, as shown in Fig. 1. This wheel f is applied loosely on a fixed horizontal transverse bar, g, which is secured rigidly at its outer end to a vertically-adjustable bracket, g¹. This bracket is secured fast to the inner side of one side of the bed-frame by means of one or more screws, g², which passes through a vertically-oblong slot made through the bed-plate frame, as shown in Fig. 2. Between the anti-friction wheel f and the bracket g¹ is a hanger or brace, h, the upper end of which is screwed into the bar g, and the lower end is yoked so as to straddle the shaft H of the wheel N and admit of the application to the under side of this shaft H, into a groove, p, formed therein, of a block, i, which is set up closely to the shaft by means of a bridge-plate and nuts j, thus drawing down the roller or wheel f upon the top of the rack e. The brace h, as well as the bracket g¹, are adjustable to regulate the holding-down pressure of the roller f in the first instance, and to compensate for the wearing away of the roller and upper surface of the rack.

It will be seen from the above description of my invention that I hold the bed-plate B down upon its ways, first, by the bar g and roller f; and second, by the brace h and shaft H. I thus make the brace serve a two-fold purpose —to wit: It assists in holding down the bar g, and it also braces the shaft H of wheel N against vibration.

Having described my invention, what I claim as new is—

The flange and rack e, dependent from the bed-plate B, and the roller f, and the bar g, in combination with the brace h and shaft H of the wheel N, substantially as described.

ALEXANDRE GASTEL.
